SAFETY SYSTEM FOR PORTABLE
ELECTRICAL APPARATUSLeo Storch, Jersey City, N. J., assignor to Western
Electric Company, Incorporated, New York,
N. Y., a corporation of New York

Application October 8, 1946, Serial No. 702,045

1 Claim. (Cl. 175—294)

1

This invention relates to safety systems for electric apparatus. The object of the invention is to insure that the exposed metal parts of such apparatus cannot rise to dangerous potentials in the event that a defect develops in the apparatus.

It is, of course, common practice to ground the chassis and other exposed metal parts of electrical apparatus to keep them at ground potential. However, such ground connections may be broken or may develop such high resistance as to permit the protected parts to rise above ground potential when there is an insulation breakdown within the apparatus. This is particularly likely to occur when the apparatus is of the portable type since the ground lead ordinarily is less well protected than in permanent installations. When such portable apparatus is of a type which operates at potentials of several thousand volts or more, special precautions to guard the operator are highly desirable.

According to the general features of this invention, the chassis and all other exposed metal parts of such apparatus are connected to ground through contacts on a relay which controls the application of power to the set. In order to insure that this connection is preserved, the relay is operated by a non-locking key and maintained operated by a holding connection shunting the key and extending through other contacts on the relay to the grounded chassis at a point other than the point of attachment of the ground lead. With this system, as will be more fully described, any electrical defect occurring in the system, which would create a hazard to the operator, will cause the immediate disconnection of the power supply from the set.

Fig. 1 of the drawing illustrates the invention as applied to a portable insulation breakdown test set of a well-known type and Fig. 2 shows a balanced source of power suitable for energizing the apparatus of Fig. 1.

In the drawing the chassis 1 is mounted on wheels 2 so that the set may be readily moved to the work location. Power is supplied from a conventional alternating current source 3 through a cord 4 and a circuit breaker 5 to the test apparatus, generally indicated at 6. This apparatus, for example, may be of any well-known type used for producing voltages and currents suitable for testing electric cables and in itself forms no part of the invention. While the voltage of the source 3 ordinarily will be that of the locally available power line, such as 440 volts between conductors 7 and 8 and about 250 volts from each of these conductors to ground at 9, the test apparatus 6

2

may be assumed to include transformers for producing higher test voltages which would be fatal to an operator in the event of an insulation breakdown within the apparatus.

5 When the set is to be used, the cord 4 is plugged into any convenient outlet 10 having a permanently grounded terminal 11 so that the line leads 7 and 8 are extended to the bus bars 12 and 13, respectively, and the conductor 14 is connected to the permanent ground. To condition the set for use the key 15 is operated momentarily to complete the operating circuit of relay 16 from the conductor 13 through the relay winding and the key to grounded conductor 14. If for any reason conductor 14 is not properly grounded, obviously the relay will not operate. Upon operation, the relay closes contact 17 to complete a circuit for the operating coil 18 of the circuit breaker 5 which operates to apply working voltage to the apparatus 6. The relay also closes contacts 19 and 20 to complete a holding circuit for the relay extending from the lower end of the relay winding through the contacts 19, conductor 21, a portion of the metal chassis 1 of the set, conductor 22 and contacts 20 to the grounded conductor 14. However, if either of the conductors 21 or 22 is not conductively connected to the chassis, the holding circuit will be incomplete and the relay will release upon the release of key 15.

30 If the relay remains operated, the chassis is necessarily connected to ground 11 and therefore cannot rise above ground potential even though failure of insulation should occur anywhere within the set.

35 It is important that the conductors 21 and 22 be attached to the chassis at separate points as indicated so that a portion of the chassis structure forms a part of the holding circuit. If this is not done, and there is a direct path between these conductors, the holding circuit will be complete even though a high resistance or an open circuit develops between these conductors and the chassis structure.

40 During the operation of the set in the normal manner, if the ground connection to the chassis should fail at any point, the holding circuit of the relay 16 is broken and the relay releases and releases the circuit breaker 5 to de-energize the high voltage apparatus 6.

45 The invention has been described with reference to the protection of a portable test set, but it is equally applicable to any other type of electrical apparatus, portable or otherwise, where a ground connection is important. The circuit shown is energized by line conductors in balanced

relation to ground as in a three phase, star-connected system, but obviously it may be used with an unbalanced source where, for example, bus bar 12 is at ground potential, as in ordinary lighting circuits. In that case conductor 14 would be connected to conductor 12 and the cord 4 would be of the two conductor type.

These and various other modifications may be made within the scope of the following claim.

What is claimed is:

In a safety system for portable electrical apparatus having a metal part normally insulated from ground, a source of power including one grounded and at least one ungrounded lead, a circuit breaker for connecting the ungrounded leads to the apparatus, an operating coil for the circuit breaker, a relay for energizing the operating coil and connecting the grounded lead to the metal part, said relay being connected between one ungrounded lead and the grounded lead, an insulated momentary contact, non-locking spring return key located in the relay circuit, contacts on the relay, one set of which are located in the

10

5

circuit breaker operating coil circuit, and a relay holding connection in parallel with the key which includes the other sets of relay contacts, a portion of the normally insulated metal part of the apparatus, and leads connecting this portion of the normally insulated metal part to the other sets of relay contacts.
